DEHALOGENATION PROCESS

Roland Kapp, Newark, and Richard Griffith, Shrewsbury, N. J., assignors to Nopco Chemical Company, Harrison, N. J., a corporation of New Jersey

No Drawing. Application February 9, 1949,
Serial No. 75,486

14 Claims. (Cl. 260—397.4)

1

This invention relates to a dehalogenation process and more particularly to a highly improved process for dehalogenating oxidized halogenated sterol compounds.

It has been known for a number of years that halogenated organic compounds could be dehalogenated to produce unsaturated organic compounds by reacting the halogenated compounds with zinc in the presence of a short chain organic acid such as acetic acid. Thus in U. S. Patent No. 1,254,866 there is disclosed a process for producing hydrocarbon oils suitable for use as drying oils wherein a natural hydrocarbon oil is first chlorinated and then the chlorinated oil is reacted with zinc in the presence of acetic acid in order to dehalogenate the chlorinated oil, thus providing a highly unsaturated hydrocarbon oil suitable for use in the paint industry.

Another example of the use of zinc as a dehalogenating agent is in the production of pure linoleic acid from tetrabrom-stearic acid. Since the various fatty acids have physical and chemical characteristics which are closely related, it is rather different to recover the individual fatty acids in pure form from natural fatty materials. However, linoleic acid may be recovered in pure form by completely saturating with halogen atoms the double bonds of all the compounds in a fatty mixture containing linoleic acid; separating by fractional crystallization the tetrahalo-stearic acid, which was formed by the halogenation of the linoleic acid, from the other halogenated fatty materials in the mixture; and subsequently dehalogenating the tetrahalo-stearic acid to re-form pure linoleic acid. It is possible to recover pure linoleic acid by such a means because of the fact that the tetrahalo-stearic acids have melting points which are rather sharp and which are separated from the melting points of the other halogenated fatty acids by a substantial number of degrees of temperature.

Another illustration of the use of zinc as a dehalogenating agent may be found in the art of sterol chemistry wherein cholesterol and similar sterols are employed to produce the sex hormones and various intermediates useful in the preparation of the sex hormones. Dehalogenation processes using zinc fit into these processes since in these processes cholesterol and other sterol compounds are first completely halogenated at the double bonds in these compounds and thereafter the halogenated compounds are subjected to strong oxidation with compounds such as chromic acid to degrade or completely split off the alkyl side chain of the sterol com-

2

ound; and after such oxidation has taken place, the oxidized halogenated compound which is obtained is dehalogenated to form the desired intermediate or the desired sex hormone. Also in the sterol field, it is rather common practice to recover stigmasterol from the mixture of sterols present in soybean oil by saturating the double bonds of the compounds in such mixture of sterols with halogen atoms and thereafter subjecting this halogenated mixture to fractional crystallization. The halogenated stigmasterol may be readily separated from the other sterols in such mixture because of the varying solubilities of these halogenated compounds. The recovered halogenated stigmasterol may then be subjected to dehalogenation with zinc to re-form the pure stigmasterol.

It is thus seen that there are a number of valuable applications of the use of zinc as a dehalogenating agent for halogenated organic compounds. In all cases in the prior art, as far as we are aware in which zinc in the presence of a short chain organic acid is used as a dehalogenating agent in such processes, the dehalogenation is carried out by admixing the halogenated compound with zinc and the short chain organic acid, e. g. acetic acid, in some suitable vessel, preferably in a vessel to which heat is applied. This is particularly true in the dehalogenation of the mixtures resulting from the chromic acid oxidation of halogenated cholesterol compounds and similar sterol compounds in processes for the production of sex hormones and intermediates suitable for the production of sex hormones. Thus in an article published by Wallis and Fernholz, J. A. C. S. 57, 1504-6 (1935), such a dehalogenation is carried out by admixing the oxidation mixture resulting from the chromic acid oxidation of cholestryl acetate dibromide with acetic acid and powdered zinc in a suitable vessel and heating this reaction mixture at about 100° C. for a period of about two hours. In U. S. Patent No. 2,180,095, which discloses the production from cholesterol and similar sterols, such as sitosterol and stigmasterol, of intermediates useful for the production of sex hormones, a similar dehalogenation process is disclosed.

The prior art processes for dehalogenating halogenated compounds with zinc have in most cases given very good yields of the desired dehalogenated compounds. An important exception, however, is in the dehalogenation of the halogenated compounds which are present in the reaction mixtures resulting from the chromic acid oxidation of halogenated sterol compounds. It

is not known just exactly why in the latter case the prior art processes do not give as good yields as desired but since the halogenated compounds are in contact with the zinc for a considerable period of time, it is entirely possible that a number of undesirable side reactions occur during the dehalogenation process which produce compounds other than those desired, thus reducing the actual yield to an amount less than that theoretically obtainable. This is probably accentuated to a considerable degree by the complexity of the mixtures resulting from the oxidation of halogenated sterol compounds. Furthermore the presence in such oxidized mixtures of many compounds other than the desired oxidized halogenated sterol compounds probably has a detrimental effect upon the dehalogenating agent reducing its efficiency and thus reducing the yield of the desired dehalogenated compounds. The longer the dehalogenating agent is in contact with this highly diverse mixture, the greater will be the reduction in its efficiency. Such an adverse effect would be an important factor in the prior art processes because of the relatively long periods of contact between the halogenated compound and the dehalogenating agent in such processes.

It is known, of course, that chromic acid oxidation of sterol compounds produces mixtures of compounds which are of a highly diverse nature and which usually contain only small amounts of the desired compounds due to the fact that it is not possible to control accurately the oxidation of the halogenated compounds so as to produce the desired oxidized materials. In other words, the oxidation, which is very severe, does not always proceed along the desired lines. In many cases the halogenated sterol compounds which are being oxidized may be split somewhere in the sterol nucleus. In fact it is for the purpose of preventing such splitting or destruction of the sterol nucleus that the sterol compound is halogenated in the first place since if the double bond or bonds in the sterol nucleus were not protected by some means such as halogenation thereof, splitting of the sterol nucleus at the double bond would occur in every case, thus resulting in a complete failure to produce any of the desired compounds.

It is the object of this invention to provide an improved process for dehalogenating halogenated sterol compounds which have been subjected to oxidation with chromic acid.

A further object of the invention is to provide a process for dehalogenating halogenated sterol compounds which have been subjected to oxidation with chromic acid which will give substantially higher yields and which will be simpler in operation than present processes for dehalogenating such materials.

Other objects of the invention will in part be obvious and will in part appear hereinafter.

It has now been discovered that the above and other objects of the invention may be accomplished by carrying out the dehalogenation of an oxidized halogenated sterol compound by a process which comprises dissolving the halogenated compound in a short chain organic acid which acid, if desired, may be admixed with up to about two and a half volumes of a suitable fat solvent, and then passing this acid solution of the halogenated compound through a suitable column packed with zinc or with a mixture of zinc and up to about equal parts of a suitable inert material. Such a dehalogenation process gives much higher yields of the desired dehalogenated com-

pound than prior art processes; furthermore, the equipment necessary to carry out this process is simpler than that required in the prior art processes and it requires less operating space than the prior art equipment. The cost of carrying out the process by this means is less than in the prior art processes since not only is the equipment which is used less expensive and less expensive to operate but also by admixing the zinc with a suitable inert material the amount of dehalogenating agent which is required will be less than that which must be used in order to carry out the dehalogenation in accordance with the prior art methods.

15 The process of the present invention is eminently suitable for use in dehalogenating any of the halogenated compounds present in reaction mixtures formed by the chromic acid oxidation of halogenated sterol compounds. Thus the 20 process of the invention is quite valuable for use in processes for the production of androsterone, cholenic acid, hydroxy cholenic acid, hydroxy norcholenic acid, and hydroxy bisnorcholenic acid and other compounds suitable for use 25 as intermediates in the production of sex hormones. It is well known, of course, that sterol compounds prior to being oxidized with chromic acid are treated so as to convert the free hydroxyl group at the 3 position to some group which will 30 not be affected by the oxidation reaction, for example, an ester group or an ether group. For the purposes of the process of our invention, it is immaterial, of course, how the 3 position of the halogenated sterol is protected during the oxidation 35 reaction. The most general practice, however, as is well known, is to form either the acetate or benzoate ester of the sterol, and then to subject the halogenated product formed from such ester to the oxidation reaction. Also, as far 40 as the process of our invention is concerned, it makes little difference as to which particular sterol is used as the initial starting material as long as it is one from which products are made by oxidizing a halogenated derivative thereof. At 45 the present time cholesterol is the sterol most frequently used as a starting material in such processes. Sitosterol, stigmasterol and similar sterols are also quite useful in producing valuable derivatives by means of such oxidation reactions. In every case where the dehalogenation of such oxidized halogenated sterol compounds is carried out in accordance with the process of the present invention, it will be found that an appreciably higher yield of the desired dehalogenated compounds will be obtained as 50 compared to the yields obtained by the prior art methods.

The dehalogenation process of our invention is carried out by dissolving the oxidized halogenated compound in a solution made up either completely of a short chain organic acid or of a mixture of a short chain organic acid and a suitable fat solvent. This acidic solution of the oxidized halogenated compound is then passed 55 through a column which is packed with zinc or which is packed with a mixture of zinc and some inert material. The short chain organic acids which we prefer to use in the process of the invention to dissolve the halogenated compounds 60 are acetic acid and propionic acid or suitable mixtures of these acids. If desired, there may be admixed with such an acid up to about two and a half parts of a suitable fat solvent for each part of acid. Thus fat solvents such as 65 ethyl ether, halogenated hydrocarbons such as

5
methylene chloride, ethylene chloride, ethylene dichloride, etc., esters such as methyl acetate and ethyl acetate, ketones such as acetone, etc., may be employed. The amount of organic acid or mixture of organic acid and fat solvent which is used as the solvent in relation to the amount of halogenated compound which is to be dehalogenated may vary, although usually it is preferred not to employ any more solvent or solvent mixture than is necessary to completely dissolve the halogenated compound which is to be dehalogenated but, if desired, larger amounts of solvent may be employed. It might be thought that the use of a halogenated fat solvent in the process would result in dehalogenation of such fat solvent and thus interfere with the dehalogenation of the compound which it is desired to dehalogenate; however, the halogenated fat solvents which are employed contain their halogen atoms in a much stronger chemically bound condition than the halogen in the halogenated compounds which it is desired to dehalogenate and therefore no detrimental results are obtained by the use of such solvents.

The column which is employed in the dehalogenation process is packed with zinc metal or a mixture of zinc metal and some inert material such as silicon carbide (sold under the trademark of "Carborundum"), glass or other suitable inert packing materials. It has been found that such inert material may be admixed with the zinc metal in up to as much as equal parts of inert material per each part of zinc without detrimentally affecting the results which are obtained. In fact, it is preferred to employ at least one part of such an inert packing material for each two parts of zinc since we have found that higher yields of the desired dehalogenated compounds are obtained when this is done as compared to when the column is packed entirely with zinc. The exact reasons for such higher yields have not been determined but we have found that such is actually the case. It may be that the inert material aids in keeping the packing in the column in a porous condition thus insuring a rapid flow of the solution of the halogenated compound through the column. Furthermore, we have also found that by packing the column with such inert material the amount of zinc which is used up in the process is considerably decreased with a decrease, of course, in the cost of the process.

The amount of zinc which is placed in the dehalogenation column will usually be somewhat greater than the amount ordinarily employed in the prior art processes for carrying out dehalogenation reactions; however, the actual amount of zinc which is used up in the reaction is no greater than that used up in the prior art processes and actually it practically always is less, and when inert materials are admixed with the zinc in the column, the amount of zinc which is used up is even smaller. Thus when an inert material, such as silicon carbide, is admixed with the zinc in the column we have found that consumption of the zinc by the process is considerably less than in the prior art dehalogenation processes. When an inert material is admixed with the zinc in the dehalogenation column, the amount of zinc plus inert material will be the same as when the column is packed completely with the zinc. In each case, the total amount of packing in the column should on the average be from about twice to above five times the amount of zinc which is theoretically necessary.

6
to completely dehalogenate the halogenated materials which are to be dehalogenated in the column. When an inert material is admixed with the zinc, it is necessary, of course, to have an amount of zinc in the column which will be sufficient to accomplish the desired dehalogenation. There is no disadvantage in using an excess amount of packing material in the column since in every case the packing material, after being washed to remove materials such as compounds produced by the reaction of the organic acid with the zinc, e. g. zinc acetate, etc., may be reused in a later dehalogenation. Therefore, in most cases, it is preferred to use an excess amount of packing in the column over what would theoretically be required to complete the dehalogenation.

The diameter and length of the dehalogenation column may vary considerably and likewise the shape of the column may be varied considerably. As a matter of convenience, it is preferred to employ a cylinder of either glass or some material such as steel and to pack such cylinder with the dehalogenating agent. The diameter or cross-sectional area of the column may be varied and ordinarily it will be governed by the size of the batch which is being passed through the column. Thus in laboratory operations, a column having a diameter of only 1 or 2 inches is suitable whereas in plant operation it is preferred to employ a column having a diameter of at least 5 or 6 inches. Likewise, the length of the column may vary and ordinarily it will depend somewhat upon the diameter of the column inasmuch as it is desirable to have the solution of the halogenated compound pass over a relatively large surface area of the dehalogenating agent. Thus if a column is employed which has a relatively large cross-sectional area, the height of the column may be substantially less than the height of a column having only a relatively small cross-sectional area.

45
In passing the solution of the halogenated organic compounds through the dehalogenation column, the solution is preferably passed through the column by gravity flow as a matter of convenience. Thus the solution may be placed in a suitable vessel located above the top of the column and the solution then slowly added to the column at the top of the column and allowed to flow rapidly through the column and as it comes out the lower end of the column it is collected in a suitable vessel. If desired, however, the solution may be added to the column at the bottom thereof and then forced upwardly by pressure flow and the solution of the dehalogenated organic compound collected from the top of the dehalogenating column. Also, if desired, the column may be placed in a horizontal position or in any position between a horizontal and a vertical position and the solution of the halogenated compound then passed therethrough from either end of the column. In such a case, particularly if the column is in a substantially horizontal position, it may be desirable to provide means for slowly rotating the column so as to insure proper contact of the halogenated organic compound with the dehalogenating agent. In all cases the rate of flow of the solution through the column should be at least approximately equal to the rate at which the solution will flow through the column because of the force of gravity when the column is in a vertical position and the solution is introduced into the column at the top thereof.

50
55
60
65
70
75
By employing columns of considerable cross-

sectional area and relatively long length, it is possible to carry out a substantially continuous dehalogenation process. In most cases, however, it is preferred to run a fairly large amount of a solution of the compound to be dehalogenated through the column and then subject the dehalogenating agent in the column to a treatment which will remove therefrom materials which may be adhered to the dehalogenating agent and which would reduce its efficiency. Since the organic acid in the solution of the halogenated compounds tends to react with the zinc to produce water-soluble zinc salts, e. g. zinc acetate, it is desirable to occasionally wash the column with water to remove such soluble zinc salts which have adhered to the zinc metal. By this means, it is possible to maintain the efficiency of the dehalogenating column at a very high level. In most cases, it is preferred to employ zinc which is at least 20 mesh in size and preferably zinc of about 10 mesh in size is utilized; however, larger or smaller sizes of zinc may be used if desired. It is usually desirable to employ as an inert material some material which is of a size slightly larger than the size of the zinc in the column so that, if desired, the zinc may later be readily separated from the inert material by a simple screening operation. Thus in the preferred packing which we employ, we utilize 10 mesh zinc and 8 mesh silicon carbide. After a dehalogenation reaction has been carried out in the column, the packing material may be removed therefrom and the zinc recovered by a simple screening of the packing material. Thereafter, of course, the recovered zinc may, if desired, be admixed again in the proper proportions with an inert packing material and used for another dehalogenation reaction. It is sometimes desirable to separate the zinc from the inert packing material following a dehalogenation reaction in order that the amount of zinc which was used up in the reaction may be determined and in order that if such zinc is to be reused it may be readmixed in the proper proportions with an inert packing material.

For a fuller understanding of the nature and objects of the invention, reference may be had to the following examples which are given merely as further illustrations of the invention and are not to be construed in a limiting sense.

Example I

A dehalogenation column was prepared by packing a glass tube, which was 90 cm. in length and 1.2 cm. in diameter, with 244 gmc. of 10-mesh zinc. This column was placed in a vertical position with a dropping funnel attached to its top with a rubber stopper. A flask was placed at the bottom of the column to receive solutions which were to be passed through the column. Two liters of an acetic acid-ethylene dichloride solution of the product resulting from the chromic acid oxidation of cholesteryl acetate dibromide were placed in the dropping funnel. The funnel was then opened sufficiently so that it required 4½ hours for the two liters of solution to enter the column. At the same time that this dehalogenation was being carried out in the column, another two liter sample of the same solvent solution of the product resulting from the chromic acid oxidation of cholesteryl acetate dibromide was subjected to dehalogenation in accordance with the prior art processes wherein the two liters of the solution were placed in a large flask and stirred for 2½ hours at 45°-50° C. with 33 gms. of zinc dust.

Both solutions after the debromination was complete were poured into water and the aqueous mixtures obtained were extracted with ethylene dichloride. The ethylene dichloride solutions which were obtained were subjected to distillation and the residues remaining after such distillations were dissolved in methanol, chilled to crystallize any cholesteryl acetate therein and then filtered to remove such crystallized cholesteryl acetate. Each methanol solution was then treated with semicarbazide hydrochloride and pyridine to precipitate the semicarbazone of dehydroisoandrosterone acetate. The sample which was dehalogenated in accordance with the prior art processes gave 1.92 gms. of semicarbazone whereas the sample which was dehalogenated by the process of the present invention gave a yield of 2.21 gms. of semicarbazone which was a 15.1% higher yield than the yield obtained by the prior art processes.

Example II

A dehalogenation column was prepared similarly as in Example I except that in this case the packing used consisted of 800 gms. of 10 mesh zinc and 800 gms. of 8 mesh silicon carbide. The glass tube which was used for the column had a length of 98 cms. and a diameter of 4.0 cms. 8.34 liters of acetic acid-ethylene dichloride solution of the product resulting from the chromic acid oxidation of cholesteryl acetate dibromide were introduced into this column over a period of 6 hours and at the same time a 9 liter sample of the same solution of the oxidation product was debrominated by the prior art process explained in Example I. The dehalogenated material in each case was worked up in the same manner as in Example I giving a yield of 11.91 gms. of semicarbazone from the process of the invention and a yield of 9.48 gms. of semicarbazone from the prior art process (the latter figure has been adjusted for the difference in starting volume). Thus there was a 25.6% greater yield with the process of the invention as compared to the yield of the prior art process.

Example III

Similar comparative runs were made in this example as in Example II using a column the same as that in Example II, but using a different batch of oxidation product. In this case the process of the invention gave a yield which was 31.5% higher than the yield of the prior art process.

Example IV

8.5 liters of an acetic acid-ethylene dichloride solution of the product resulting from the chromic acid oxidation of cholesteryl acetate dibromide was diluted with 20 liters of water and then extracted five successive times with ethylene dichloride using 2 liter, 1 liter and then 3 different 500 ml. portions of ethylene dichloride. The combined ethylene dichloride extracts were concentrated to 2.84 liters by distillation under reduced pressure and in the presence of 50 gms. of potassium acetate. One liter of acetic acid was admixed with the 2.84 liters of the ethylene dichloride solution and the resulting solution then passed through a glass column 84 cms. in length and 2.5 cms. in diameter which was packed with 300 gms. of 10 mesh zinc and 300 gms. of 8 mesh silicon carbide. The rate of flow of the solution into the column was adjusted so that a period of 6 hours was required to introduce all of the solution into the column.

At the same time an equal sized aliquot of the same oxidation product was debrominated in accordance with the prior art process. The process of the present invention gave a yield of 11.43 gms. of semicarbazone whereas the prior art process gave a yield of 9.82 gms. Thus the process of the present invention gave a 16.4% higher yield than the process of the prior art.

Example V

Another dehalogenation was carried out using the column employed in Example I with the exception that in this case the column was packed with 113 gms. of 10 mesh zinc mixed with Fenske (glass) packing in alternate zones about 30 mm. deep. The rate of introduction of the solution into the column was 1 hour and 25 minutes for 2 liters of the acid solution of the oxidized halogenated product. At the same time that this dehalogenation was being carried out, an aliquot of the same solution was being dehalogenated by the prior art process. In this case the process of the present invention gave a yield of 1.54 gms. of semicarbazone whereas the prior art process gave a yield of only 1.41 gms. Thus the process of the invention gave a yield which was 9.2% higher than the yield obtained with the prior art process.

It is evident from the above description and examples that the process of the present invention gives a substantially higher yield than the processes used in the prior art for dehalogenating oxidized halogenated sterol compounds; furthermore, since it has always been believed in the prior art to be necessary to heat the reaction mixture and to employ means of continuously mixing the zinc with the material to be dehalogenated, it is obvious that the apparatus and operating space required in the prior art take up more space and involve more expense than is the case in the process of the present invention. Furthermore, the process of the invention is much simpler than the processes of the prior art since it may be carried out by merely allowing the acid solution of the material which is to be dehalogenated to flow through a column packed with zinc. As has been pointed out above, it is possible to cut down considerably on the amount of zinc which is required by admixing with the zinc a relatively large amount of inert material such as silicon carbide, glass or other suitable inert material. Thus it is evident that the process of our invention, although it may seem to be a rather simple change from the prior art teachings, is actually a great advance in the art of dehalogenating oxidized halogenated sterol compounds. Although the time required to dehalogenate a large quantity of a halogenated compound is just as great when our new process is used as when the prior art methods are employed, the length of time during which each molecule of halogenated compound and dehalogenated compound produced therefrom is in contact with a dehalogenating agent is far less when our new process is used than when the prior art methods are employed. This much shorter time of contact of the individual molecules with the dehalogenating agent is possibly one of the reasons why our process gives so much higher yields than the prior art processes since a shorter contact time undoubtedly reduces the amount of undesirable side reactions which occur.

Having described our invention what we claim as new and desire to secure by Letters Patent is:

1. In a process for dehalogenating a halogenated sterol compound which has been subjected to oxidation wherein the dehalogenation of the oxidized halogenated sterol compound is accomplished by reacting the oxidized halogenated sterol compound with zinc in the presence of a short chain fatty acid, the improvement which comprises slowly introducing an acid solution comprising the oxidized halogenated sterol compound and a short chain fatty acid into a column packed with a packing material selected from the group consisting of zinc and mixtures of zinc and inert material in which the inert material may comprise up to about 50% of the mixture, passing the acid solution which has been introduced into the column through the column at a rate which is at least approximately equal to the rate at which the solution will flow through the column because of the force of gravity when the column is in a vertical position and the solution is introduced into the column at the top thereof, and recovering the desired dehalogenated sterol compound from the acid solution after the acid solution has passed through the packed column.
2. The process of claim 1 wherein the acid solution of the oxidized halogenated sterol compound contains up to about five parts of an inert organic fat solvent for each two parts of short chain fatty acid.
3. The process of claim 1 wherein the short chain fatty acid which is employed is acetic acid.
4. The process of claim 1 wherein the packing material in the column is a mixture of zinc and silicon carbide.
5. The process of claim 1 wherein the acid solution of the oxidized halogenated sterol compound contains up to about five parts of ethylene dichloride for each two parts of short chain fatty acid.
6. The process of claim 1 wherein the acid solution of the oxidized halogenated sterol compound contains up to about five parts of ethylene dichloride for each two parts of short chain fatty acid and wherein the short chain fatty acid is acetic acid.
7. The process of claim 1 wherein the acid solution of the oxidized halogenated sterol compound contains up to about five parts of ethylene dichloride for each two parts of short chain fatty acid, wherein the short chain fatty acid is acetic acid, and wherein the packing material in the column is a mixture of zinc and silicon carbide.
8. In a process for dehalogenating oxidized halogenated derivatives of cholesterol obtained by the chromic acid oxidation of a halogenated cholesterol compound wherein the dehalogenation is accomplished by reacting the oxidized halogenated compounds with zinc in the presence of a short chain fatty acid, the improvement which comprises slowly introducing an acid solution comprising the oxidized halogenated derivative and a short chain fatty acid into a column packed with a packing material selected from the group consisting of zinc and mixtures of zinc and inert material in which the inert material may comprise up to about 50% of the mixture, passing the acid solution which has been introduced into the column through the column at a rate which is at least approximately equal to the rate at which the solution will flow through the column because of the force of gravity when the column is in a vertical position and the solution is introduced into the column at the top thereof, and recovering the desired dehalogenated sterol

11

compound from the acid solution after the acid solution has passed through the packed column.

9. The process of claim 8 wherein the packing material in the column is a mixture of zinc and silicon carbide.

10. The process of claim 8 wherein the short chain fatty acid which is employed is acetic acid.

11. The process of claim 8 wherein the acid solution of the oxidized halogenated sterol compound contains up to about five parts of an inert organic fat solvent for each two parts of short chain fatty acid.

12. The process of claim 8 wherein the acid solution of the oxidized halogenated sterol compound contains up to about five parts of ethylene dichloride for each two parts of short chain fatty acid. 15

12

13. The process of claim 8 wherein the acid solution of the oxidized halogenated sterol compound contains up to about five parts of ethylene dichloride for each two parts of short chain fatty acid and wherein the packing material in the column is a mixture of zinc and silicon carbide.

14. The process of claim 8 wherein the acid solution of the oxidized halogenated sterol compound contains up to about five parts of ethylene dichloride for each two parts of short chain fatty acid, wherein the short chain fatty acid is acetic acid, and wherein the packing material in the column is a mixture of zinc and silicon carbide.
